ACCESS DOOR FITTING FOR TANKS

Francis J. Pepersack, Towson, Md., assignor to
 The Glenn L. Martin Company, Middle River,
 Md., a corporation of Maryland

Application August 15, 1942, Serial No. 454,985

5 Claims. (Cl. 150—3)

1

The invention to be described pertains to access door fittings for tanks, and particularly for tanks adapted to contain liquid hydrocarbons, and comprising a rubber-like cell confined by a rigid housing structure. Tanks of this nature are used as fuel and oil tanks for airplanes.

They are fitted into the different parts of the fuselage or wings so that the normal structure provides the rigid housing element of the tank. An illustration of this practice is found in Gray 10 et al. Patent No. 2,102,590 disclosing a cellular form of tank applied to aircraft construction. However, this cellular form of tank is also applicable to other kinds of transport vehicles such as ships, motor trucks, and freight cars.

The general purpose of this invention is to provide a cellular tank of the type indicated with a relatively large access door or closure which will facilitate manufacture of the tank cell and its assembly in a housing structure, and also afford access to the entire interior of the cell, as is often convenient or necessary. In so doing, it is desirable to employ a door or closure of the same flexible, rubber-like material as the cell and to give the cell opening and the door or closure sufficient reinforcement so that they may be easily assembled together and subsequently clamped in closing relation.

More specifically, it is intended to provide an access door and tank cell opening with a continuous, peripherally extending reinforcement which will maintain the shape of both of these parts and yet flex readily in any direction.

An additional object of the invention resides in the provision of opposed clamping elements provided with spacing means for preventing undue compression of the cell material which is often of a rubber subject to cold flow deformation.

A further specific object is to modify the construction of the tank cell around its opening and the access door around its periphery so as to replace a portion of the cell construction which is most susceptible to cold flow with a material which is resistant thereto.

A further object of the invention, the details of which will be pointed out subsequently, is to provide a form of clamping means for the tank cell and access door which may be used without modification for tank cells of widely varying thickness with the addition or subtraction of a molding strip of resilient material.

One of the more specific objects is to provide a special form of threaded means which may be used with the cell clamping members to support

2

the tank cell on the rigid housing structure and assist in the assembly of the access door.

Still other features of novelty contributing to the efficiency and simplicity of the fitting construction of this invention will be pointed out in connection with the following detailed description of several illustrative embodiments taken in connection with the accompanying drawings, in which

Fig. 1 shows a fragmentary plan view of an access door fitting for a circular tank opening, the view being partly broken away to show certain details in section;

Fig. 2 is a fragmentary plan view of a clamping member of the fitting;

Fig. 3 is a vertical transverse section to reduced scale taken along the line III—III of Fig. 1;

Fig. 4 is a similar vertical transverse section taken along the line IV—IV of Fig. 1;

Fig. 5 is a transverse vertical section similar to Fig. 4 in most respects, but showing a different form of tank cell;

Fig. 6 is a vertical transverse section showing a modified form of clamping means;

Fig. 7 is a vertical transverse section of the two clamping members employed in the modification of Fig. 6; and

Fig. 8 shows partially in elevation and partially in transverse section a special form of clamping means and hanger arrangement for the tank cell.

Referring to Figs. 3 and 4, a tank cell of flexible rubber-like material is designated generally as 10 and is provided with a rigid housing structure 12, which in this instance is the surface structure of an aircraft. It will be noted that the tank cell 10 is formed to provide a relatively large opening 14 which is circular in the illustrated embodiments. An access door 16 of the same or similar material as the tank cell, is made slightly smaller and of the same shape as the opening 14 into which it is fitted.

An outer clamping flange 18 and an inner clamping flange 20 engage the corresponding sides of the tank cell 10 and door or closure 16 so as to span their juncture and clamp these two tank cell parts in sealing relation. The outer circular clamping flange 18 is provided with a series of spaced holes 22 for receiving the shanks of a set of screws 24 which are threadedly engaged in a correspondingly spaced set of tapped bosses 26 formed on the inner clamping flange 20, as shown in Fig. 3. The clamping portion of the outer flange 18 is formed to provide rounded gripping edges 28, 28 and a series of gripping ridges or similar formations 30, 30. Flange 20

has identical projections in the form of gripping edges 32 and gripping ridges 34 acting in opposition to those of the clamping flange 18.

A particular feature of the inner clamping flange 20 is a series of spacer elements 36 extending between the screw holes 22, as shown best in Fig. 2. The spacer elements 36 are preferably of arcuate shape or may be of short lengths and arranged on the arc of a circle having the radius of the centers of the screw openings 22. It is the function of the spacer elements 36 to fit between the peripheral edges of the tank cell 10 and the access door 16, and to engage the opposite part of the outer clamping flange 18 so as to limit the threaded screws 24 to a predetermined clamping engagement with the compressible tank cell and door material.

Figs. 1, 3 and 4 show the manner in which the opposed peripheries of the tank cell 10 and the access door of closure 16 are reinforced by means of a hoop 38 and an identical but slightly smaller hoop 40, respectively. Preferably, the tank cell hoop 38 and the door hoop 40 are of rectangular cross-section and formed of braided steel wire impregnated and covered with a synthetic rubber material such as neoprene or other equivalent material. As used herein, the term "hoop" is not limited to a circular ring, but denotes a continuous element having the configuration of the tank cell opening 14.

The tank cell 10 is of the self-sealing, bullet-proof type specifically disclosed and claimed in Gray and DeWeese patent application Serial No. 338,052, filed May 31, 1940, entitled "Self-sealing tank." The cell 10 comprises four principal layers which are adhesively bonded together and arranged in the manner shown. These layers are a soft, vulcanized outer layer 42, a middle layer 44 of crude, unvulcanized rubber which is subject to cold flow and loss of shape under continued clamping pressure, a highly, liquid hydrocarbon resistant, inner layer 46 of neoprene or equivalent synthetic rubber composition, and a relatively thin, inner liner layer 48 composed of a strong fabric impregnated with neoprene, or equivalent non-fabric material. Because of susceptibility to cold flow, the middle layer 44 of crude unvulcanized rubber is replaced by a circular layer 50 extending as a ring about the tank cell opening 14. The circular layer of filler element 50 is preferably formed of fabric impregnated with neoprene or other synthetic rubber-like material of equivalent properties.

Means for retaining the reinforcing hoop 38 in position around the periphery of the tank cell opening 14 are shown in Fig. 4 as comprising a braid reinforcement 52 which is wrapped around the edge of the opening so as to cover the hoop 38 and extend over the inner and outer surfaces of the tank cell 10. This braid reinforcement or continuous binding is impregnated with neoprene or the like and secured in the position shown by Fig. 4. The outer side of the tank cell 10 has a seam cover 54, of balloon cloth fabric impregnated with neoprene or the like, and provided with an upstanding flange 56 extending within the space between the tank cell opening 14 and the spacer elements 36, or clamping screws 24. This seam cover 54 will also be secured in place by a suitable adhesive. Since the means for securing the door reinforcing hoop 40 in position and the construction of the door 16 around its edge are identical with that which have been described for the opening of the tank

cell 10, it is believed unnecessary to repeat those details.

The clamping means and tank cell opening and access door reinforcements which have been described with respect to the illustrative embodiment of Figs. 1 to 4 may be adapted without modification to a tank cell 58 of single layer construction. The tank cell 58 shown in Fig. 5 is provided with an opening 60 for receiving an access door 62. The tank cell 58 comprises a thin wall layer 64 of flexible rubber-like material such as neoprene or other synthetic rubber, which is resistant to the action of liquid hydrocarbons. About the opening 60 the rubber-like layer 64 is faced and reinforced by identical inner and outer layers 66 and 68, respectively, adhesively secured thereto and composed of heavy fabric material impregnated with neoprene or the equivalent. By reason of the much less thickness of the tank cell 58, it is necessary to provide a resilient molding or filler strip 70 of any suitable rubber material which will take up the space and permit the use of the same clamping flanges 18 and 20 previously described. The outer surface of the door 62 will also be provided with a molding or filler strip 72 about its periphery and extending beyond the point of contact with the outer clamping flange 18.

The reinforcement of the tank cell opening 60 and the periphery of the door 62 is by means of hoops 74 and 76, respectively, which are identical with those which have been disclosed in connection with the principal embodiment. Corresponding use is also made of an impregnated braid reinforcement 78 as retaining means for the cell hoop 74, it being noted that the molding or filler strips 70 and 72 are provided with adhesively secured fabric reinforcements 80 and 82 on their respective inner faces. An outer reinforcement layer 84, preferably of balloon cloth fabric impregnated with neoprene, covers the outer end of the braid reinforcement 78 and is provided with an upstanding flange 86 extending generally parallel with the thickness of the hoop 74. As will be appreciated from an inspection of Fig. 5, the door or closure reinforcing hoop 76 is secured in place in an identical manner.

Figs. 6, 7 and 8 illustrate a modified form of clamping means which may be used with the tank cell 10 and access door 16 of the principal embodiment. The only difference is in an outer clamping flange 180 which is provided with a troughlike recess 182 for receiving the heads of the threaded clamping screws, the other ends of which threadedly engage an inner clamping flange 200 in the same way as has been set forth. It will also be noted that the clamping flanges 180 and 200, which are of circular shape to correspond with the cell opening, lack the intermediate clamping ridges used in Figs. 3 and 4.

With reference to Fig. 7, the inner clamping flange 200 is further modified in its provision for a spaced series of transverse holes or openings 202 through its web 204 for permitting free drainage of gasoline or other liquid hydrocarbon.

In Fig. 8 there is shown a special screw or bolt 240 which functions both as a threaded clamping means for the outer and inner flanges 180 and 200, and also as a hanger for securing the attached tank cell to its rigid housing structure 12. The bolt 240 is provided intermediate its length with a nut-shaped head 242 above a washer 244 received in the outer face recess 182 of the flange 180. By means of the head 242, a threaded

shank part 246 may be turned into the inner clamping member 200 to draw it toward the outer clamping member 180. The outer end of the bolt 240 has a larger threaded shank 248 engaged by a wing nut 250 and locked by a wire 252 when clamped down upon the plane portions of the structure 12 through an intermediate clamping washer 254. In this manner, the tank cell 10 and its access door or closure 16 are secured or hung to the rigid housing structure 12.

It will be apparent that the modified form of clamping means illustrated in Figs. 6, 7, and 8 may be applied either to the multiple layer cell 10 or to the single layer tank cell 58 with the use of rubber molding or fillers 10 and 12.

The access door fitting which has been described in detail is readily attached to the tank cell and an adequate, but non-destructive, sealing is obtained with the clamping means of this invention. With the special form of cell opening and door edge defining hoops of this invention, the mating edges are fully protected against tearing and damage so that the access door may be removed and replaced as often as may be necessary.

While a circular access door fitting has been shown illustratively, other forms of opening and fittings may be employed as convenient. It will also be understood that various changes may be made in the details of construction and arrangement of the elements of this fitting without departing from the spirit of the invention and the scope of the appended claims.

Having thus described my invention, what I claim as new and desire to secure by Letters Patent of the United States is:

1. An access door construction for a flexible, rubber-like tank cell provided with a relatively large generally circular opening in its wall, comprising, a door of the same material as the tank cell fitted within said opening, a first flexible hoop of reinforced, rubber-like material positioned against the periphery of the circular opening of the tank cell, means for securing said first flexible hoop to the tank cell, said means comprising a continuous strip covering said hoop, said strip being secured to the inner and outer surfaces of said wall around said opening, a second flexible hoop of reinforced, rubber-like material extending around the periphery of the door, similar means for securing said second flexible hoop to the door, a continuous outer clamping flange spanning the juncture between the tank cell and the door, a continuous inner clamping flange arranged in opposition to the outer flange, spacer elements on one of the clamping flanges and extending between the two hoops for limiting the clamping action of the clamping flanges on the tank cell and the door, and separable means engaging the clamping flanges between the spacer elements to maintain them in clamping position.

2. An access door construction for a liquid fuel or lubricant tank cell comprising one or more layers of rubber-like material subject to cold flow and provided with a relatively large opening in its wall, comprising, a door of the tank cell material fitted within said opening, a first flexible hoop of reinforced, rubber-like material positioned against the periphery of the opening of the cell, continuous binding means secured to the inner and outer surfaces of said wall around said opening for securing said first flexible hoop to the cell, a second flexible hoop

of reinforced, rubber-like material extending around the periphery of the door, similar continuous binding means for securing said second flexible hoop to the door, an outer clamping flange spanning the juncture between the cell opening and the door, an inner clamping flange arranged in opposition to the outer flange, means at spaced positions on one of the clamping flanges and extending between the two hoops for limiting the clamping action of the clamping flanges on the tank cell and the door, and detachable threaded means engaging the clamping flanges to maintain them in clamping position, said clamping flanges being formed with opposed projections for gripping the tank cell and the door.

3. The combination comprising a hydrocarbon liquid container cell formed of three layers of rubber-like material, the intermediate layer of which is subject to cold flow, said tank cell being provided with a relatively large opening in its wall, a closure of the tank cell wall material fitted within said opening, a first ring-shaped filler layer of material resistant to cold flow inserted between two of the layers of rubber-like material around the tank cell opening and in place of the intermediate layer, said intermediate layer being cut away from the tank cell opening to receive the first filler layer, a second ring-shaped filler layer of material resistant to cold flow inserted between two of the layers of rubber-like material around the periphery of the closure and in place of the intermediate layer, said intermediate layer being cut away from the closure periphery to receive the second filler layer, a binder strip secured to the inner and outer faces of said closure around said opening, an outer clamping flange coextensive with the tank cell opening and spanning the juncture between the tank cell opening and the closure, an inner clamping flange coextensive with the tank cell opening and arranged in opposition to the outer flange, means on one of the flanges and extending between the cell opening and closure peripheries for predeterminedly limiting the clamping action of the flanges on the tank cell and the closure, and separable means engaging the clamping flanges to maintain them in clamping position.

4. The combination comprising a hydrocarbon liquid container cell formed of three layers of rubber-like material, the intermediate layer of which is subject to cold flow, said tank cell being provided with a relatively large opening in its wall, a closure of the tank cell wall material fitted within said opening, a first ring-shaped filler layer of material resistant to cold flow inserted between two of the layers of rubber-like material around the tank cell opening and in place of the intermediate layer, said intermediate layer being cut away from the tank cell opening to receive the first filler layer, a second ring-shaped filler layer of material resistant to cold flow inserted between two of the layers of rubber-like material around the periphery of the closure and in place of the intermediate layer, said intermediate layer being cut away from the closure periphery to receive the second filler layer, a binder strip secured to the inner and outer faces of said cell wall and said closure around said opening, an outer clamping flange coextensive with the tank cell opening and spanning the juncture between the tank cell opening and the closure, an inner clamping flange coextensive with the tank cell opening and arranged in opposition to the outer flange, means on one of the flanges and extending between the cell opening and closure peripheries for prede-

terminedly limiting the clamping action of the flanges on the tank cell and the closure, separable screws engaging the clasping flanges to maintain them in clamping position, and a rigid housing structure confining the tank cell, the closure, and the clamping flanges, at least one of said screws having a nut threaded on one end and a washer thereunder for engaging and hanging the tank cell to the rigid housing structure.

5. An access door construction for a single layer, flexible, rubber-like tank cell provided with a circular opening in its wall, comprising a door of similar material to the cell fitted within said opening, a resilient molding strip of appreciable thickness secured to and facing the tank cell layer around its opening, another resilient molding strip of appreciable thickness secured to and facing the door around its periphery, a first flexible hoop of reinforced, rubber-like material positioned against the periphery of the circular open-

ing of the tank cell, means for securing said first flexible hoop to the tank cell and its molding strip, said means comprising a continuous binder strip covering said hoop, said strip being secured to the inner and outer surfaces of said cell wall and molding strip around said opening, a second flexible hoop of reinforced, rubber-like material extending around the periphery of the door, similar means for securing said second flexible hoop to the door and its molding strip, an outer clamping flange spanning the juncture between the cell opening and the door, an inner clamping flange arranged in opposition to the outer flange, means on one of the clamping flanges and extending between the two hoops for predeterminedly limiting the clamping action of the clamping flanges, and detachable threaded means engaging the clamping flanges to maintain them in clamping position.

FRANCIS J. PEPE SACK.
